UNITED STATES PATENT OFFICE

2,662,988

BASE FOR MOTORS

James A. McKim, Fort Wayne, Ind., assignor to
 General Electric Company, a corporation of
 New York

Application July 15, 1948, Serial No. 38,923

5 Claims. (Cl. 310—91)

1

This invention relates to supporting structures for machines and more particularly to such structures which are used in mounting dynamo-electric machines.

In the design of supporting structures for machines, it is frequently desirable to provide an arrangement which permits the supporting element to be mounted in any one of four positions, namely, conventional, inverted, right side wall, or left side wall, without altering the relative position of the machine. It is also desirable to provide a supporting structure which can be permanently secured to an external surface and which permits removal and replacement of the machine without removal of the supporting element. Such an arrangement is particularly desirable in the design of certain dynamo-electric machines such as fractional horsepower electric motors for installation in gasoline pumps since different manufacturers may specify different locations for securing the motor, for instance, inverted suspension, conventional mounting, or supported by the right side wall or the left side wall of the pump. In either case, the motor is required to have the same relative position and it is, therefore, necessary to provide a supporting structure which can be used with the same motor in any one of the four mounting positions. It is also desirable in the interests of economical construction to provide a supporting arrangement which directly engages the clamping bolts of the motor.

An object of this invention is to provide an improved supporting structure for a machine.

Another object of this invention is to provide an improved supporting structure for a machine which can be mounted in any one of four positions without changing the relative position of the machine.

A further object of this invention is to provide an improved supporting structure for a machine which permits removal of the machine without removal of the supporting element.

Further objects and advantages of this invention will become apparent and the invention will be better understood by reference to the following description and the accompanying drawing. The features of novelty which characterize this invention will be pointed out in the claims annexed to and forming a part of this specification.

In the drawing, Fig. 1 is a side elevational view, partly in section, illustrating the improved supporting structure of this invention utilized to support a motor in an inverted position; Fig. 2

2

is a view in perspective of the base member of Fig. 1; Fig. 3 illustrates in detail the slotted opening and washer feature of this invention; and Fig. 4 is a side elevational view showing the application of the improved supporting structure of this invention for conventional mounting of a motor.

In accordance with this invention, there is provided a U-shaped base member, one leg of which is provided with two holes which slip over one end respectively of two clamp bolts which are secured to the machine. The other leg of the base is provided with two slotted openings which fit over the other ends respectively of the two clamp bolts. The neck of the slotted opening is slightly wider than the diameter of the clamp bolts and the interior portion of the slot is substantially larger than the width of the neck. After the base is slipped into place, a washer is placed over the end of each clamp bolt and fitted into the interior portion of the slotted openings. Conventional clamping nuts and washers are then mounted on each end of the clamp bolts. Thus, the weight of the machine is supported on one side by engagement of the holes in one base leg with the clamp bolts and on the other side by the base through the washers in the slotted openings rather than by friction between the clamping nuts and base.

Referring now to Fig. 1, there is shown a fractional horsepower motor 1 provided with conventional end shields 2 and a shaft extension 3. Each end shield is provided with a plurality of equally spaced projections 4 on the outer periphery thereof and formed integral therewith. The end shields 2 are secured to the central portion 5 of the motor by a plurality of equally spaced longitudinal clamp bolts 6 which extend through openings in the projections 4. These clamp bolts also serve as mounting members, as will be hereinafter described. The ends 7 and 8 respectively of the clamp bolts 6 are on the exterior of the end shields 2 and spaced from the outer periphery thereof. The ends 7 of the clamp bolts 6 are threaded to engage tapped holes in the corresponding projections 4 and to receive clamping nuts 10, as will be hereinafter described. The ends 8 of the clamp bolts are threaded to receive clamping bolts 9. A U-shaped base member 11 supports the motor 1 and is provided with a central portion 12 adapted to be mounted on an exterior surface 13 in any convenient manner, such as by bolts 14. The base member 11 is provided with leg portions 15 and 16 which respectively engage

the ends 7 and 8 of the clamp bolts 6, in the manner now to be described.

Referring now to Fig. 2, the base member 11 is shown provided with a plurality of slotted openings 17 in its central portion 12 through which the mounting bolts 14 project. The leg portion 15 is provided with two openings 18 (only one being here shown) which are only slightly larger than and are adapted to slide over the ends 7 of two of the clamp bolts 6. The other leg portion 16 of the base member 11 is provided with two slotted openings 19. Each of these openings is provided with a neck portion 20 which is only slightly wider than the diameter of the ends 8 of the clamp bolts 6 and an interior portion 21 which is substantially wider than the width of the neck portion 20.

To mount the motor 1 on the base 11, washers 22 are positioned on the ends 8 of two of the clamping bolts 6 adjacent the clamping nuts 9. The ends 7 of the two clamping bolts 6 are then inserted through the two holes 18 of the leg portion 15 and the other ends 8 are slid through the neck portions 20 of the slotted opening 19 into the interior portions 21. Two washers 23 are next positioned on the ends 8 of the clamp bolts 6 so that they fit snugly within the interior portions 21 of the slotted openings 22. The clamping nuts 10 are then placed on the ends 7 securing the leg portion 15 tightly against the projections 4 and washers 24 and clamping nuts 25 are positioned on the other ends 8 to hold washers 23 in place and to secure the leg portion 16 against the clamping nuts 9.

Referring now to Fig. 3, it can be readily seen that the weight of the machine regardless of the position of the base member 11 is supported on one side by the leg portion 15 of the base 11 and on the other side by the washer 23 within the interior portion 21 of the slotted opening 19 rather than by the clamping action of the washers 22 and 24 and the nuts 25. Referring now to Fig. 4, it can also be seen that the motor 1 can be mounted in the same relative position as in Fig. 1 but with the base 11 mounted in the conventional position rather than the inverted position. It will also be apparent that the motor 1 can be readily removed by merely removing the clamping nuts 10 from the ends 7 of the clamping bolts 6 and the clamping nuts 25, washers 24, and washers 23 from the other ends 8. The ends 8 of the clamp bolts 6 can then be merely slid out of the slotted openings 19 and the ends 7 pulled out of the holes 18. Thus, removal and replacement of the motor does not necessitate dismounting of the base member 11.

While there is illustrated and described a particular embodiment of this invention, modifications thereof will occur to those skilled in the art. I desire it to be understood, therefore, that this invention is not to be limited to the particular arrangement disclosed and I intend in the appended claims to cover all modifications which do not depart from the spirit and scope of this invention.

What I claim as new and desire to secure by Letters Patent of the United States is:

1. A machine comprising a frame member, a longitudinal mounting member secured to said frame member and having its ends positioned respectively on the exterior of said frame member and spaced from the outer periphery thereof, a base member for said machine having a portion adapted to be mounted on an external surface and two supporting portions for engaging the ends of said mounting member, one of said por-

tions having an opening formed therein with one end of said mounting member being arranged therein, the other of said portions having a slotted opening formed therein with its neck portion being larger than the other end of said mounting member and its interior portion being substantially larger than said neck portion, washer means having an outside dimension larger than said neck portion of said slotted opening, said washer means being positioned on said other end of said mounting member and seated within said interior portion of said slotted opening whereby the weight of said machine in any position is supported by said base member through said washer means in said slotted opening and said machine can be removed without removing said base or said mounting member, and fastening means on the ends of said mounting member for holding said one supporting portion and said washer means in place.

2. A machine comprising a frame member, a longitudinal mounting member secured to said frame member and having its ends positioned respectively on the exterior of said frame member and spaced from the outer periphery thereof, a U-shaped base member for said machine having a central portion adapted to be mounted on an external surface and two leg portions for engaging the ends of said mounting member, one of said leg portions having an opening formed therein with one end of said mounting member being arranged therein, the other of said leg portions having a slotted opening formed therein with its neck portion being larger than the other end of said mounting member and its interior portion being substantially larger than said neck portion, washer means having an outside diameter larger than said neck portion of said slotted opening, said washer means being positioned on said other end of said mounting member and seated within said interior portion of said slotted opening whereby the weight of said machine in any position is supported by said base member through said washer means in said slotted opening and said machine can be removed without removing said base or said mounting member, and fastening means on the ends of said mounting member for holding said one supporting portion and said washer means in place.

3. A machine comprising a frame member, a plurality of equally spaced longitudinal mounting members secured to said frame member, the ends of each of said mounting members being respectively positioned on the exterior of said frame member and spaced from the outer periphery thereof, a U-shaped base member for said machine having a central portion adapted to be mounted on an external surface and two leg portions for respectively engaging the ends of two of said mounting members, one of said leg portions having two openings formed therein with first ends of two of said mounting members being respectively arranged therein, the other of said leg portions having two slotted openings formed therein, each of said slotted openings having its neck portion larger than the other ends of said two mounting members and its interior portion substantially larger than said neck portion, two washers each having an outside dimension larger than said neck portion of said slotted opening, said washers being positioned respectively on said other ends of said two mounting members and seated within said interior portion of each of said slotted openings whereby the weight of said machine in any position is supported by

said base member through said washers in said slotted openings and said machine can be removed without removing said base or said mounting members, and fastening means on the ends of said two mounting members for holding said one leg portion and said washers in place.

4. A dynamoelectric machine comprising a frame having two end shields, a clamping member for securing said end shields to said machine, the ends of said clamping members being positioned respectively on the exterior of said end shields and spaced from the outer periphery thereof, a U-shaped base member for said machine having a central portion adapted to be mounted on an external surface and two leg portions for engaging the ends of said clamping members, one of said leg portions having an opening formed therein with one end of said clamping member being arranged therein, the other of said leg portions having a slotted opening formed therein with its neck portion being larger than the other end of said clamping member and its interior portion being substantially larger than said neck portion, a washer having an outside dimension larger than said neck portion of said slotted opening, said washer being positioned on said other end of said clamping member and seated within said interior portion of said slotted opening whereby the weight of said machine in any position is supported by said base member through said washer and said slotted opening and said machine can be removed without removing said base or said clamping member, and fastening means on the ends of said clamping members for holding said one leg portion and said washer in place.

5. A dynamoelectric machine comprising a frame having two end shields, a plurality of equally spaced longitudinal clamping members for securing said end shields to said frame with the ends of each of said clamping members being positioned respectively on the exterior of said end shields and spaced from the outer periphery thereof, a U-shaped base member for said machine having a central portion adapted to be mounted on an external surface and two leg por-

5 tions for engaging the ends of two of said clamping members, one of said leg portions having two openings formed therein with first ends of two of said clamping members being respectively arranged therein, the other of said leg portions having two slotted openings formed therein, each of said slotted openings having its neck portion larger than the other ends of said two clamping members and its interior portion substantially larger than said neck portion, two washers each having an outside dimension larger than said neck portion of said slotted openings, said washers being positioned respectively on the other ends of said two clamping members and seated snugly within said interior portion of said slotted openings whereby the weight of said machine in any position is supported by said base member through said washers in said slotted openings and said machine can be removed without removing said base or said clamping members, and fastening means on the ends of said two clamping members for holding said one leg portion and said washers in place.
